STEP BODIED AUTOMOBILE

John T. Le Rose, Box 14032, Benjamin Franklin Station,
Washington, D.C. 20044

Filed Apr. 12, 1968, Ser. No. 12,346

Term of patent 7 years

Int. Cl. D12—08

U.S. Cl. D14—3

FIG. 3

FIG. 4

FIG. 5

FIG. 7

FIG. 6

FIG. 8

FIG. 1 is a front perspective view of a step bodied automobile showing my new design.

FIGURE 2 is a rear perspective view thereof.

FIGURE 3 is a side elevational view thereof.

FIGURE 4 is a top plan view thereof.

FIGURE 5 is a rear perspective view thereof.

FIGURE 6 is a front perspective view thereof.

FIGURE 7 is a cross sectional view of the rear of a step bodied automobile as taken on lines 7-7 of FIGURE 4.

FIGURE 8 is a cross sectional view of the front of a step bodied automobile as taken on lines 8-8 of FIGURE 4.

The dominant features of my new design reside in the full line portions thereof.

I claim:

The ornamental design for a step bodied automobile, as shown and described.
